[57] CLAIM

The ornamental design for a support for tomato plants
or the like, as shown and described.

DESCRIPTION

FIG. 1 is a top perspective view of a support for tomato
plants or the like showing my new design;

FIG. 2 is a bottom perspective view thereof;

FIG. 3 is a front elevational view thereof, the rear and
adjacent sides being identical in appearance;

FIG. 4 is a top plan view thereof; and

FIG. 5 is a bottom plan view thereof.

FIG. 1

FIG. 2

FIG. 3

FIG. 4

FIG. 5
